UNITED STATES PATENT OFFICE.

JOSEPH TABER, OF MILLBROOK, NEW YORK.

SPIRAL PROPELLER.

Application filed June 17, 1920. Serial No. 389,681.

To all whom it may concern:

Be it known that I, JOSEPH TABER, a citizen of the United States, residing at Millbrook, in the county of Dutchess and State 5 of New York, have invented certain new and useful Improvements in a Spiral Propeller, of which the following is a specification.

The present invention relates to improvements in spiral propellers and more particularly to a spiral propeller which is affixed to the bow of a vessel for the more speedy propulsion thereof.

The further object is to provide a propeller of the above type which is simple in construction, compact and durable, and one which may be manufactured at a reasonably low cost.

In the drawings:

20 Fig. 1 is a view in side elevation of my invention showing clearly the exterior construction of the propeller and a carrying means therefor.

25 Fig. 2 is a view in longitudinal cross section showing the interior construction and the means for driving the propeller.

Fig. 3 is a view in cross section taken on line 3—3 of Fig. 2.

In the drawings 10 designates a portion of 30 the bow of a vessel in which one end 11 of the propeller is journaled. This end is preferably in the form of a sleeve and its projecting portion is within the inner end of the propeller cone 12. The propeller, as thus 35 constituted, is in the nature of a long hollow shell made in two interfitting parts or section for convenience in assembling; the parts being welded or otherwise secured at the joint to provide an integral whole. A carrying member or keel 13 has one end fixed to the bow of the vessel and its other end provided with a bearing 14 in which the outer end of the propeller cone 12 operates.

40 The propeller cone is freely rotatable, as a unit, on its bearings and may be driven from the main or engine shaft in a manner such as hereinafter described.

45 As will be observed upon reference to the drawings, the propeller cone 12 is provided with external spiral fins or flanges and that

these fins or flanges extend the entire length of the cone. It is to be understood that any number of these fins or flanges may be employed and that I am not limited to any particular width or dimensions.

55 The main drive shaft 15 extends through the sleeve 11 and has its outer end loosely mounted in a bearing 16 near the outer end of the propeller cone 12. A suitable bearing bracket, such as shown at 17, may be used 60 to support this shaft inwardly of its outer end.

65 The countershaft 18 also extends into the propeller cone 12 in slightly spaced relation to the inner wall of the cone and carries a pinion 19 which meshes with a pinion 20 on the main drive shaft 15. The countershaft 18 also carries spaced drive pinions 21 which mesh with the teeth of circular racks 22 on the inner face of the sleeve 11 so that movement of the drive shaft 15 will be duly imparted to the propeller cone. Counter shaft 18 is supported at its opposite end in suitable bearing brackets 23 and 24, the latter being loosely suspended from shaft 15, as 70 75 illustrated.

75 The propeller cone being free to rotate as above described can be driven at any desired speed from the main drive shaft 15. It will also be noted that because of its length and the fact that keel 13 is employed the propeller will materially aid in the steering of the boat and at the same time insure a speedy 80 propulsion thereof.

85 Water may be excluded at the point where the propeller shell is journaled in the hull by packing or other means in a manner well known in the art.

What is claimed is:

90 The combination with a boat hull of a propeller shell formed of integral sections, spiral fins provided externally of one section, circular racks provided internally of the other section, a drive shaft extending from the hull into the shell, a gear on said shaft, 95 and gears connecting the drive shaft gear with the circular rack of the propeller shell.

In testimony whereof I affix my signature.

JOSEPH TABER.
